United States Patent Office.

MELVIN JINCKS, OF DANSVILLE, NEW YORK.

Letters Patent No. 77,984, dated May 19, 1868.

MATCH-SAFES.

The Schedule referred to in these Letters Patent and making part of the same.

TO ALL WHOM IT MAY CONCERN:

Be it known that I, MELVIN JINCKS, of Dansville, in the county of Livingston, and State of New York, have invented certain new and useful Improvements in Match-Safes; and I do hereby declare that the following is a full, clear, and exact description thereof, reference being had to the accompanying drawings, and to the letters of reference marked thereon, which form a part of this specification:

Figure 1 is a view in perspective of a match-safe embracing my improvements.

Figure 2, a vertical longitudinal section of the same.

Figure 3, a perspective view of the rocking-floor of the safe, as seen from below; and

Figure 4 a vertical transverse section of the safe.

The improvements claimed under the patent consist—

First, in arranging an oscillating or rocking-floor in a match-safe, in such manner that the slide, which draws out the matches, shall tilt the floor, and insure its depositing a match upon the slide, which then returns the floor to its horizontal position.

Second, in combining with the slide, striking-hands, so arranged as to ignite the match with certainty on its withdrawal.

In the accompanying drawings, A represents the chamber, which contains the matches, and B the oscillating or rocking-floor of the same. C is the slide, which withdraws the matches, and c the thumb-piece, by which it is moved. It is returned to position, after being drawn out, by the gum-spring d, attached to a pin at the rear extremity of the safe. The slide C is provided with a horn, e, which, by striking against the lugs f f g of the floor, tilts the latter to deposit the match and afterwards returns it to position.

D D' are the striking-hands, furnished with fingers, to ignite the match when it is drawn through them.

E is the door, by which the safe is filled, and i a spring, which closes an opening in the bottom of the channel k, when the slide is withdrawn.

The operation of the safe is as follows:

After being filled with matches by the lid or door E, the slide C is drawn out by its thumb-piece c. When the horn e of the slide strikes the lug g on the rocking-floor, it thereby tilts the latter over towards the channel k, and causes it to drop a match therein. The match is then drawn out between the hands D D', striking successively against the fingers of the same in its passage, and causing it to be ignited with certainty. The spring i prevents the end of the match from dropping through the opening in the bottom of channel k, when the slide is withdrawn. The horn e, in striking the lugs f f of the rocking-floor, throws the latter back to its horizontal position after the match has been deposited in the channel.

Having thus fully described my improved match-safe, what I claim therein as new, and desire to secure by Letters Patent, is—

1. The rocking-floor B, arranged as described, so as to be tilted by the slide C in its withdrawal, and returned to its horizontal position after depositing the match.
2. The combination of the floor B, slide C, and striking-hands D D', when arranged and operating in the manner and for the purposes set forth.

In testimony that I claim the foregoing as my own, I affix my signature in presence of two witnesses.

MELVIN JINCKS.
